(57) **CLAIM**

The ornamental design for an tubing clip for dialysis treatment as shown and described.

DESCRIPTION

FIG. 1 is a perspective view of an tubing clip for dialysis treatment showing the new design in a partial opened configuration;

FIG. 2 is a first side view of the tubing clip for dialysis treatment of FIG. 1;

FIG. 3 is a second side view of the tubing clip for dialysis treatment of FIG. 1;

FIG. 4 is a top view of the tubing clip for dialysis treatment of FIG. 1;

FIG. 5 is a bottom view of the tubing clip for dialysis treatment of FIG. 1;

FIG. 6 is a front view of the tubing clip for dialysis treatment of FIG. 1;

FIG. 7 is a rear view of the tubing clip for dialysis treatment of FIG. 1;

FIG. 8 is an alternate perspective view of the tubing clip for dialysis treatment of FIG. 1;

FIG. 9 is a perspective view of the tubing clip for dialysis treatment showing the new design in a closed configuration; FIG. 10 is a first side view of the tubing clip for dialysis treatment of FIG. 9;

FIG. 11 is a second side view of the tubing clip for dialysis treatment of FIG. 9;

FIG. 12 is a top view of the tubing clip for dialysis treatment of FIG. 9;

FIG. 13 is a bottom view of the tubing clip for dialysis treatment of FIG. 9;

FIG. 14 is a front view of the tubing clip for dialysis treatment of FIG. 9; and,

FIG. 15 is a rear view of the tubing clip for dialysis treatment of FIG. 9.
